FLUID-FLOW DIRECTING APPARATUS

Bobby J. Helm, Pasadena, Calif., and Woodrow W. Bledsoe, Mesquite, Tex., assignors to Progress-O-Matic, Incorporated, a corporation of California

Filed Apr. 8, 1963, Ser. No. 271,394

2 Claims. (Cl. 137—608)

The present invention relates to a fluid-flow directing apparatus and more particularly to such an apparatus selectively adjustable to direct a fluid stream through associated equipment and alternatively to by-pass the equipment with the fluid stream.

The apparatus was invented in response to problems encountered in connection with the cleaning of cotton borne in an air stream and is suitably illustrated by reference to such an operational environment and purpose. When cotton is picked, it is normally accompanied by various amounts of leaves, twigs, debris and other extraneous material collectively referred to as "trash." The extent of such trash varies greatly as a result of the picking conditions and the method of picking employed. Thus, at times it is necessary to remove large quantities of trash while at other times no such removal is necessary. Since trash removal requires power, wears the trash removing equipment, and tends to lower the grade of the cotton, it has been recognized as desirable to avoid when not needed. Cotton cleaners, whether mounted in mobile cotton pickers or gleaners or in stationary installations, such as cotton gins, normally receive the cotton and trash in air stream, segregate the trash from the cotton for independent discharge, and return the cotton to the air stream for subsequent accumulation, transport, storage, or processing. The air stream is normally created by connecting a conduit having the cleaner as a part thereof to the intake of a blower. Thus, cotton is drawn into the conduit and carried through the cleaner on its way to the blower, in advance of which it is deflected to avoid direct engagement with the blower. The cleaners are normally integral parts of such conduits and, where employed, are continuously utilized whenever the air stream is in operation. No suitable structure has been available for quickly and easily by-passing such cleaners when cotton is handled which requires no trash removal and for quickly and easily redirecting the air stream through the cleaner when trash removal is desired.

An object of the present invention is, therefore, to provide an improved fluid-flow directing apparatus.

Another object is to provide a fluid-flow directing apparatus adjustable to direct fluid and fluid-borne material through associated equipment and to by-pass such equipment by readjustment of the apparatus.

Another object is to provide an apparatus for directing an air stream and material borne by the air stream into processing equipment and to by-pass such equipment by simple and easily performed re-adjustment of the apparatus.

Another object is to provide such apparatus that is fully effective in accomplishing its directing and by-passing functions with a minimum of congestion, entanglement, and/or clogging.

Another object is to provide such an apparatus which in directing and by-passing adjustment has a minimum of resistance to flow therethrough.

Another object is to provide a fluid-flow directing apparatus of the character described which is economical to produce, efficient to employ, durable, and fully effective in accomplishing its intended purposes.

Further objects and advantages will become apparent in the subsequent description in the specification.

In the drawing:

2

FIG. 1 is a side elevation of a cotton cleaner incorporating the fluid-flow directing apparatus of the present invention and shown in association with a fragmentarily represented intake conduit, outlet conduit, and debris discharge conduit.

FIG. 2 is a transverse section taken through the structure shown in FIG. 1 on line 2—2.

Referring in greater detail to the drawing, a cotton cleaner is shown at 10 connected to an upwardly extended inlet conduit 11, an outwardly extended outlet conduit 12, and a downwardly extended debris discharging conduit 13. The cleaner and its associated conduits may be mobile, as employed in cotton pickers and gleaners, or stationary, as employed in cotton gins and other cotton processing equipment.

As best shown in FIG. 2, the inlet conduit 11 and the outlet conduit 12 are in substantially right angular relation and have spaced ends connected to the housing 10 providing relative adjacent or inner edges 15 and 16 and 15 relative remote or outer edges 17 and 18, to which reference is subsequently made. Said inner edges of the conduits are interconnected by an oblique wall 19 of the housing 10. The housing also employs a bottom wall 20, opposite side walls 21 and 22, a top wall 23, and 25 bevelled corner walls 25 which, in association with front and rear walls 26 and 27, define a chamber 28 which is air tight except for communication with the conduits 11, 12, and 13. The designated walls are conveniently formed of sheet metal and in addition to their air and 30 cotton confining function preferably provide sufficient strength to support bearings utilized in the mounting of certain internal structure to which reference is now made.

A pair of drive shafts 30 are journaled between the front and rear walls 26 and 27 in suitable bearings 31 35 mounted on said walls. As shown, one of the shafts is located centrally near the top of the housing and the other shaft is located in the lower portion of the housing. Each shaft mounts a cleaning cylinder 32 for unitary rotation therewith which has peripherally extended saw 40 teeth 33. Such cleaning cylinders are well known in the art and are not here described in greater detail. During operation, the upper most cleaning cylinder is rotated in a counterclockwise direction while the lower cylinder is rotated in the opposite direction.

45 Substantially equidistant from the walls 21, 23, and 24, a doffing shaft 35 is rotatably mounted between the front and rear walls 26 and 27 in similar bearings 36. A doffer 37 of any suitable form is mounted on the doffing shaft in a position in close proximity to the periphery of the upper cleaning cylinder 32. During operation, the doffer is rotated in a clockwise direction, as viewed, at a peripheral velocity substantially greater than the peripheral velocity of the cleaning cylinder. A doffing bar 40 is rigidly mounted between the front and rear walls 26 and 50 27 closely adjacent to the periphery of the upper cleaning cylinder and in following relation to the doffer 37 with respect to the direction of cylinder rotation. As is well known in the art, a plurality of grid sections 41 are 55 similarly rigidly mounted in the housing adjacent to the periphery of the upper cleaning cylinders and in following relation to the doffing bar.

60 As will be understood, a blower, not shown, is utilized to cause a high velocity air stream to move into the housing 10 through the inlet conduit 11 and out of the housing through the outlet conduit 12. For reasons soon to become apparent, an auxiliary wall 45 is mounted between the front and rear walls 26 and 27 and is extended inwardly of the housing 10 from the outer edge 65 17 of the inlet conduit 11 and constitutes a conduit extension. It has been found convenient to continue the wall 40 arcuately about the lower peripheral portion of the

cleaning cylinder 32 in order to form a huller bar for the cleaner. Somewhat similarly, an auxiliary wall 46 is mounted between the front and rear walls 26 and 27 and is extended inwardly of the housing 10 from the outer edge 18 of the outlet conduit. To avoid excessive discharge of air and air borne cotton out of the debris conduit 13, an air seal 47 is mounted on the wall 22 and conveniently takes the form of a flexible flap of belting material held in the position shown by any suitable bracket means. Since a small amount of cotton sometimes inadvertently passes the air seal 47, it is also desirable to utilize a reclaimed brush 16 mounted in the position shown to return such cotton against the lower cleaning cylinder so it can be snagged by the saw teeth and salvaged while debris descends out of the conduit 13.

To facilitate the doffing operation, a compression plate 50 is mounted on the upper wall 23 between the front and rear walls 26 and 27 in adjacent relation to the periphery of the cylinder 32 and during operation serves to compress cotton carried by the cylinder against the teeth immediately prior to engagement by the doffer 37.

Substantially mid-way between the inlet of the inlet conduit 11 to the housing 10 and the outlet of the outlet conduit 12, a pair of shafts 55 are mounted between the front and rear walls 26 and 27 by bearings 56 borne by said walls. It will be noted that one shaft is above the other, that the lower shaft is preferably substantially aligned with the inner edge 15 of the inlet conduit 11 and is spaced from the oblique wall 19 approximately the width of the inlet conduit. The other shaft is in spaced adjacent relation to the lower shaft but is upwardly and inwardly thereof. A baffle 57 of sheet metal or the like is rigidly mounted on the lower shaft and downwardly extended therefrom. The baffle 57 is of such length that it can be brought into alternate engagement with the oblique wall 19 and the auxiliary wall 45 which actually are extensions of the inlet conduit 11 and can be regarded. A baffle 58 of similar material is rigidly mounted on the upper shaft and extended therefrom into the outlet of the outlet conduit 12. The baffle 58 is of sufficient length to permit alternate with the extended end thereof with the inner edge 16 of the outlet conduit and the auxiliary wall 46. The extended end of the baffle 58 is preferably slightly angled toward the outlet conduit to facilitate direction of air and air borne cotton thereto. The shafts 55 are spaced slightly to permit ease of operation. The resulting gap is blocked by mounting a stationary baffle 59 rigidly between the front and rear walls 26 and 27 in bridging relation to said gap.

To permit convenient positioning of the baffles 57 and 58, handles 65 are radially extended from the shaft 55 exteriorly of the housing 10 and are each provided with suitable latching means 66 for releasably holding the handles in positions corresponding to the alternate positions of their respective baffles.

Operation

The operation of the fluid-flow directing apparatus of the present invention is believed to be readily apparent and is briefly summarized at this point. Assuming that cotton, not shown, having a large proportion of trash mixed therewith is being drawn in air stream inwardly through the inlet conduit 11 for cleaning and subsequent discharge of the cotton in air stream through the outlet conduit 12, the handles 65 are positioned to locate their baffles 57 and 58 in the positions shown in full line in FIG. 2. The entering air stream with its cotton impinges on the periphery of the upper cleaning cylinder 32 where the cotton is snagged by the teeth 33. As the cylinder rotates, trash is thrown from the cylinder in the well known manner. Such trash is also accompanied by small amounts of cotton and descends onto the lower cleaning cylinder where the cotton is again snagged by the teeth. As the lower cylinder rotates, such cotton and accompanying debris are carried under the air seal 47. The air seal aids in sep-

arating the trash from the cotton for gravitationally descent of the trash. The reclaimer brush facilitates maintenance of the cotton on the teeth for subsequent recovery. The trash descends through the debris conduit

5 13 and is discharged. The cotton snagged on the teeth of the lower cylinder continues back into the air stream of the inlet conduit which doffs the cotton and carries it upwardly for re-engagement with the teeth of the upper cylinder. Cotton snagged by the teeth of the upper cylinder is doffed by the doffer 37 and discharged into the air stream passing from the housing out the outlet conduit 12. It is to be understood that the described cleaning operation is not an essential part of the present invention but typifies an operation requiring the directing of the fluid stream and carried material into a processing apparatus. The oblique disposition of the stationary baffle 59 facilitates the directing of the incoming air stream properly against the upper cylinder 32.

When the operator of the described apparatus notes that 20 cotton entering through the inlet conduit 11 is so clean that it should by-pass the cleaner, the handles 65 are relocated to pivot the baffles 57 and 58 against the outer edges 17 and 18 of their respective inlet conduits. Actually, the baffles engage the auxiliary walls 45 and 46 which are regarded as inward extensions of said outer edges. So arranged, the air passing in the inlet conduit 11 and out the outlet conduit 12 tends to hold the baffles 57 and 58 in position. The air stream and its material effectively by-passes the cleaning structure in the chamber 25 30 35 40 45 50 55 28 with the oblique wall 19 and the baffles 57 and 58 together with the front and rear walls 26 and 27 constituting a by-pass conduit. This by-pass conduit can be visualized as having an opening between the auxiliary walls 45 and 46 which communicates with the chamber 28 and over which the housing 10 is mounted. The opening is closed by positioning the baffles in the dashed line position and opened and air directed in and back out of said opening and the chamber by positioning the baffles in the full line position shown in FIG. 2.

Manipulation of the handles 65 permits instant positioning of the baffles 57 and 58. Thus, an operator can immediately condition the described apparatus to direct the air stream and air borne cotton and trash into the chamber 28 where it is processed in the manner described. Alternatively, the operator can position the baffles completely to by-pass the cleaning operation so that clean cotton need not be reduced in grade by the action of the saw teeth and associated structure and the loss of power required for cleaning as well as the obvious wear on the cleaning equipment can be avoided.

The fluid-flow directing apparatus of the present invention has proved highly effective in the described environment but is not limited to such utilization. The baffles in their association with the oblique wall 19, and the inner and outer edges of the inlet conduit 11 and the outlet conduit 12 provide effective fluid stream directing or bypassing as determined by baffle adjustment.

Although the invention has been herein shown and described in what is conceived to be the most practical and preferred embodiment, it is recognized that departures may be made therefrom within the scope of the invention, which is not to be limited to the details disclosed herein but is to be accorded the full scope of the claims so as to embrace any and all equivalent devices and apparatus.

Having described our invention, what we claim as new and desire to secure by Letters Patent is:

1. The combination of an elongated fluid conduit having opposite walls, a pair of baffles, means mounting the baffles for pivotal movement about adjacent axes transversely of the conduit intermediate the walls, said baffles being oppositely extended from their respective axes longitudinally of the conduit and pivotal between deflecting positions in engagement with one of the walls and by-pass positions substantially parallel to said wall, and a deflector plate rigidly mounted in the conduit between the axes of

the baffles in bridging relation between the baffles and extended obliquely away from the wall engaged by the baffles when the baffles are in deflecting positions.

2. The combination of a housing having a chamber defined by a plurality of interconnected walls, a fluid inlet, and a fluid outlet, the inlet and outlet being in substantially right angular relation and there being a wall of the housing obliquely extended therebetween; a pair of adjacent shafts mounted in substantially parallel relation to the oblique wall between the inlet and the outlet; fluid obstructions mounted adjacent to the inlet and to the outlet and inwardly extended opposite to their respective inlet and outlet from the oblique wall; and a pair of baffles individually mounted on the shafts and oppositely extended therefrom for pivotal movement between positions with their extended ends engaged with said oblique wall adjacent to the inlet and outlet respectively to direct fluid from the inlet into the chamber and from the chamber into the outlet and to positions substantially parallel to said oblique

wall and their extended ends engaged with respective obstructions with the oblique wall defining a conduit directly from the inlet to the outlet, the pivotally mounted baffles being spaced to form a gap therebetween; a fixed baffle rigidly mounted in the housing in bridging relation to said gap and directed toward said chamber obliquely to the pivotal baffles.
